UNITED STATES PATENT OFFICE.

MINOR E. CHAMBERLAIN, OF LEBANON, MISSOURI.

REINFORCED CONCRETE CONSTRUCTION.

1,119,066.

Specification of Letters Patent.

Patented Dec. 1, 1914.

Application filed April 1, 1914. Serial No. 828,655.

To all whom it may concern:

Be it known that I, MINOR E. CHAMBERLAIN, a citizen of the United States, residing in the city of Lebanon and State of Missouri, have invented a new and useful Reinforced Concrete Construction, of which the following is a specification.

This invention relates to reinforced concrete construction, including posts, columns, 10 walls and various forms of devices and structures composed of concrete provided with reinforcements.

An object of the invention is to provide a concrete post having sections of metallic 15 reinforcements embedded therein, and reinforcing elements engaging with and uniting the different sections of reinforcements and also serving to strengthen the reinforcements and the post structure at the point of 20 union of said sections.

Another object is to provide an improved reinforced concrete post comprising a monolithic body composed of concrete, in combination with a reinforcement embedded in 25 the concrete and composed of sheet metal bent and folded so as to form two arms or vanes of double thickness and two arms or vanes of single thickness, and one or more supplemental reinforcements each composed 30 of sheet metal bent and folded to form one arm of double thickness and two arms of single thickness, for engaging and co-operating with the first mentioned reinforcement to strengthen the arms of single thickness 35 on said reinforcement.

A further object is to provide a reinforced concrete construction comprising a body of concrete, and a series of metallic reinforcements embedded in said concrete and composed 40 of sheet metal bent and folded to provide laterally extending arms, in combination with metal reinforcing plates engaging with said arms and connecting said reinforcements to strengthen the structure 45 against lateral and longitudinal stresses.

Another object is to provide a reinforced concrete post or column comprising a concrete body, and metal reinforcements embedded in said body near the surface thereof, in combination with a metallic reinforcement embedded in said body near the center thereof, and a series of metallic plates connecting said reinforcements.

Various other objects and advantages will 55 appear from the following detailed descrip-

tion, reference being made to the accompanying drawings in which—

Figure 1 is a longitudinal sectional view of a post embodying my invention. Fig. 2 is a view enlarged relative to Fig. 1 illustrating the reinforcing connecting devices or elements by which the different sections of the reinforcements are connected and strengthened. Fig. 3 is a cross sectional view on the line 3—3 of Fig. 2. Fig. 4 is a side elevation of a reinforcing device consisting of separate sections of sheet metal one of which is provided with arms of double thickness and arms of single thickness, the arms of single thickness being strengthened and reinforced by the separate reinforcing element. Fig. 5 is an enlarged perspective view of one end of a reinforcing element. Fig. 6 is a sectional view of a part of a concrete structure embodying sheet metal reinforcements connected by reinforcing plates. Fig. 7 is a vertical sectional view of a part of a concrete structure illustrating portions of the reinforcements before being embedded in the concrete. Fig. 8 is a perspective view of one of the connecting plates by which the vertical reinforcing devices are connected. Fig. 9 is a cross sectional view of a post or column provided with a plurality of longitudinal 85 reinforcing devices connected by a number of plates embedded in the concrete. Fig. 10 is a view illustrating the reinforcing devices with the concrete removed. Fig. 11 is a perspective view illustrating the form of the 90 connecting plates utilized in the structure illustrated in Figs. 1 and 10.

A post utilizing the reinforcements illustrated in Figs. 1 to 5, inclusive, comprises a concrete body 1 of the desired dimensions so that the reinforcements may be embedded therein. The reinforcements consist of a number of sections of sheet metal bent and folded to form two arms or vanes 2 of double thickness, and two arms 3 of single 100 thickness at right angles to the arms of double thickness. The arms 2 and 3 extend radially substantially from a common center, and the reinforcing sections employed are intended to be arranged end to end. When 105 so arranged the abutting sections are connected and reinforced by suitable reinforcing connections also composed of sheet metal.

Each reinforcing connection is composed 110

2
of sheet metal bent to form a central arm 4 of double thickness adapted to embrace the arms 3 of single thickness in the abutting reinforcing sections, as illustrated in Figs. 5 1 and 2. The connecting reinforcements also include two laterally extending arms 5 of single thickness which press against the arms 2 of the reinforcing sections when the various elements are assembled, as illustrated in Fig. 3. After the reinforcing connections have been arranged upon the abutting reinforcing sections the arms or vanes are stamped to form openings 6 and laterally extending projections 7. The laterally extending projections 7 on the reinforcing connections interlock with the arms 2 and 3 of the reinforcing sections, so that the various parts of the reinforcement are firmly secured together. The openings 6 formed by the projections 7 receive the concrete, so that the reinforcement and the concrete become very firmly united. The arms or vanes 2 and 3 are also provided with extensions 7 so that the concrete becomes seated in holes and 25 embeds the lateral projections upon the reinforcing sections throughout their length.

The reinforcement illustrated in Fig. 4 consists of a single section A of reinforcement, composed of sheet metal bent to form 30 arms 2 of double thickness and arms 3 of single thickness, (Fig. 5) precisely like the sections of reinforcements just described. For one or more of the arms 3 of single thickness there is an auxiliary reinforcement 35 extending substantially from end to end of the reinforcement A. The auxiliary reinforcement is formed precisely like the reinforcing connections between the different sections of reinforcements above described, except that it extends substantially from end to end of the main reinforcement. The auxiliary reinforcement consists of an arm 4 of double thickness embracing the arm 3 of single thickness, and it consists further of 40 two laterally extending arms 5 pressing against the arms 2 of double thickness. All of the arms of the reinforcement thus assembled are stamped to form holes 6 and to provide lateral extensions 7. The reinforcement 45 thus formed is embedded in the concrete and extends substantially from end to end of the post, constituting a very strong and substantial reinforcement.

The structure illustrated in Figs. 6, 7 and 55 8 consists of a concrete body, and a series of reinforcing members similar to the reinforcements above described as employed in the concrete posts. The sheet metal forming said reinforcements is bent and folded to 60 form two arms 8 of double thickness and two arms 9 of single thickness. The reinforcements thus formed are spaced at suitable intervals, and the arms 8 and 9 on the different reinforcements are connected by reinforcing plates, the plates arranged in con-

nection with the arms 8 being in different horizontal planes from the plates connected to the arms 9, so that the various connecting plates occupy a staggered relation. Each plate consists of two metallic sections 10 stamped to form interlocking lateral extensions 11 whereby the plates are held together. The plates 10 are provided with laterally extended portions 12, and the arms 8 and 9 are received between the plates 10, 70 the lateral extensions 12 bearing against the arms on the reinforcements as illustrated in Fig. 6. After being assembled the arms on the reinforcements and the extensions 12 on the connecting plates are stamped to form 75 openings 12 and interlocking projections 13, thereby firmly connecting the various parts of the reinforcements to receive all of the lateral and longitudinal stresses of the structure. This structure is particularly adapted 80 for use in the construction of walls and large 85 columns and pedestals and the like.

The structure illustrated in Figs. 9, 10 and 11 includes a concrete body of any desired shape embedding in its center one of 90 the reinforcing devices 14 of the type previously described. There are also embedded in the concrete a series of reinforcing devices 13 parallel with the central reinforcement 14. Each reinforcement 15 is formed 95 precisely similar to the auxiliary reinforcement illustrated in Fig. 4 and consists of one arm of double thickness and two laterally extending arms of single thickness. The reinforcements 15 are connected with 100 the central reinforcement 14 by a plurality of connecting devices 16. Each connecting device 16 consists of a doubled section of sheet metal embraced between the arms of the reinforcement 15 and embracing one of 105 the arms of the reinforcement 14. The edges of the member 16 are bent to provide lateral extensions 17, and when the reinforcements are assembled the engaging portions of the several reinforcements are 110 stamped to form lateral extensions 18 to interlock the parts and openings or holes in which the concrete solidifies. The structure illustrated in Figs. 9 and 10 is adapted 115 particularly for use in constructing posts of 115 large size, columns, pedestals and various other concrete structures.

It will be understood that there may be various modifications in the construction and arrangement of the different elements of the 120 invention without departure from the spirit of the invention. I do not restrict myself to precise details, but

What I claim and desire to secure by Letters Patent of the United States is:

1. In a monolithic concrete structure, a concrete body, and a pair of sheet metal reinforcements each comprising a single sheet folded to provide four perpendicularly disposed lateral wings, two of which wings 130

are of a double and the remaining two of a single thickness of the sheet, the single wings being in alinement with each other, a reinforcing connection clamped closely upon the edges of single thickness of both of said reinforcements, and projections on said reinforcements engaging said connection, substantially as described.

2. In combination, a pair of parallel sheet metal reinforcements each comprising a single sheet folded to provide four perpendicularly disposed lateral wings, two of which wings are of a double and the remaining two of a single thickness of the sheet, the single wings being in alinement with each other, a sheet metal connection clamped closely against the wings of single thickness on both of said reinforcements, registering passages through said connection and through said plates, and concrete embedding said plates and said connections and being within said passages, substantially as described.

3. Reinforced concrete construction, comprising a concrete body, a number of parallel sheet metal reinforcements each comprising a single sheet folded to provide four lateral wings, two of which wings are of a double and the remaining two of a single

thickness of the sheet, the single wings being in alinement with each other, plates connecting one of the wings of single thickness of each of said reinforcements with one of the wings of single thickness of another reinforcement, and devices interlocking said plates with said wings, substantially as described.

4. In a monolithic concrete structure, a concrete body, and a number of aligned sheet metal reinforcements each comprising a single sheet folded to provide four perpendicularly disposed lateral wings, two of which wings are of a double and the remaining two of a single thickness of the sheet, the single wings being in alinement with each other, plates clamped closely upon the wings of single thickness and constituting connections between said reinforcements, and interlocking connections holding said plates in engagement with said wings of single thickness, substantially as described.

In witness whereof, I have signed this specification in the presence of two subscribing witnesses.

MINOR E. CHAMBERLAIN.

Witnesses:
